UNITED STATES PATENT OFFICE

147,084

DESIGN FOR A DISPLAY RACK

Jean O. Reinecke, Oak Park, Ill., assignor to The
Griffith Laboratories, Inc., Chicago, Ill., a cor-
poration of Illinois

Application March 29, 1946, Serial No. 128,097

Term of patent 14 years

(Cl. D80—9)

To all whom it may concern:

Be it known that I, Jean O. Reinecke, a citizen of the United States, residing at Oak Park, in the county of Cook, State of Illinois, have invented a new, original, and ornamental Design for Display Rack, of which the following is a specification, reference being had to the accompanying drawing, forming part thereof, in which:

Fig. 1 is a perspective view of a display rack showing my new design, and

Fig. 2 is a plan view of the display rack of Fig. 1, showing my new design.

I claim:

The ornamental design for a display rack, as shown.

JEAN O. REINECKE.
